ILLUMINATED SIGN

John J. Shively, New York, N. Y., and Miles Pennybacker, West Orange, N. J., assignors to Neosign Corporation, a corporation of Delaware

Application May 28, 1935, Serial No. 23,832

9 Claims. (Cl. 40—132)

This invention relates to an illuminated sign employing a grid of tubing filled with neon or other suitable gas. As such tubes and the manner of operating them is well known, the grid 5 will not be described in detail.

The object of the invention is to provide a complete unit assembly or "chassis" that is simple and cheap to manufacture and which is adapted for use in a number of different casings, the chassis 10 carrying all of the operating parts of the sign as hereinafter described, and the casing serving merely to enclose the chassis, there being no working parts mounted on the casing.

Heretofore, it has been customary to assemble 15 the parts such as the grid, reflectors, transformer, etc. in or upon the casing of the sign. Such a complete sign is shown in the copending application Serial No. 22,333 filed May 20, 1935, entitled "Illuminated sign". Such a sign must 20 have the parts secured to the outer casing and usually this is of bakelite or other insulating material which, if cracked or damaged, permits the parts to shift position. Furthermore, if the casing is broken, it is necessary to disassemble the 25 entire sign in order to replace the same.

The present invention makes it possible to assemble all of the parts in a metal frame which is then mounted in an outer insulating casing from 30 which it can be removed without disassembling the parts. This also facilitates manufacture and has other advantages and objects which will be apparent from the following specification of a preferred embodiment of the invention.

In the accompanying drawings:

Figure 1 is a rear view of a sign chassis embodying the invention without the transformer;

Figure 2 is a view of the top of the chassis, Figure 1;

Figure 3 is a view of the bottom of the chassis, Figure 1;

Figure 4 is an end view of chassis, Figure 1;

Figure 5 is a sectional view on the line 5—5, Figure 1;

Figure 6 is a view of the bottom of the chassis, Figure 1, with the transformer mounted thereon;

Figure 7 is a sectional view on the line 7—7, Figure 6;

Figure 8 is a view partly in section, similar to Figure 7 but showing an insulating casing enclosing the chassis; and

Figure 9 is an external rear view of the complete chassis and casing, Figure 8.

The frame 10 is stamped or otherwise suitably formed—preferably from a sheet of metal. The 55 blank is stamped flat, the rectangular center por-

tion 11 being removed and the laterally extending portions 12, 13, 14, 15 being bent rearwardly as shown to form the top, bottom and sides of the frame.

The rear edge of the top is slotted as shown at 16 to receive the forked ends 17 of the cross members 18, the purpose of which will be presently described. These members have the outwardly extending tongues 19 which extend into corresponding slots 20 in the bottom 13.

The frame and cross members being complete as just described, the other parts may be assembled therein. These parts comprise a transparent panel 21 of glass or the like which fits within the space between the top, bottom and sides of frame 10 and closes the rectangular opening in the front of same.

Behind this panel or glass 21 is positioned the grid 22 of luminous tubing, as previously referred to. This grid may lie flat against the inner surface of glass 21, and is provided with the usual electrode terminals 23, 24.

In the rear of this grid may be positioned a suitable reflector 25 or a separate reflector strip for each horizontal leg of the grid, as more fully described in the copending application Serial No. 11,903, filed March 20, 1935, entitled "Luminous tube sign", it being understood that said strips 25 are separated from each other and from the metal frame by suitable air gaps or insulation 26. The reflector is preferably of metal.

Strips of insulating material 27—preferably resilient, such as sponge rubber—are placed against the rear of said reflector strips, these rubber strips corresponding to each of the cross members 18.

The members 18 now have their tongues 19 inserted in slots 20 and are pressed down until the forked ends 17 thereof lie in the slots 16 in the rear edge of the top 12. The frame and the tongues 19 left extending from this edge between each pair of slots 17 are bent downwards over the members 18 and secure same in place. Thus the entire assembly is secured together without the use of screws or other separate fastening means.

The arrangement and assembly of parts are such that when a plurality of metal reflector strips 25 are used, each strip is insulated from the others and from the frame 10. This prevents any short circuiting or other harmful effect due to the close proximity of the metal reflector strips to the glass grid 22, these strips being insulated via the air gaps 26 and the rubber strip 27.

The complete chassis as just described can now be mounted in a suitable casing that will sur-

round and enclose all parts thereof except the panel 21 which is left exposed.

The terminals 23, 24 being connected to a suitable source of current, the grid 22 will be illuminated and the panel 21 will have the appearance of a sheet of neon glow. By marking suitable indicia thereon, the device acts as a sign or advertising device.

It is customary to use alternating current, 110 to 125 volts with these signs, using a transformer to increase the voltage sufficiently to actuate the grid 22 and when it is desired to mount the transformer on the chassis just described it can be done by providing the usual transformer 29 with the brackets 30—30 which are attached by screws or any other suitable means to the top and bottom of frame 10. The transformer is mounted on these brackets in any suitable manner, and the secondary terminals 31 of same are connected to the terminals 23, 24 of the grid and the primary terminals 32 are connected to the alternating current supply. This arrangement provides a chassis complete with transformer, and there are no connections between these parts to be made or broken in case the chassis is to be removed from the casing.

Figures 8 and 9 disclose a chassis complete with transformer as just described mounted in a front casing 33 and a rear casing 34 of insulating material. These casings completely surround and enclose all metal parts and prevent all liability of injury to the user in case any metal part comes in contact with the secondary circuit of the transformer.

The screws 35 holding the casings 33, 34 together do not connect with any of the interior parts.

The flexible cord 36 connects to the primary terminals 32 of the transformer and passes through a slot 37 in the rear casing, so that the casings 33, 34 may be separated by removing screws 35 and the chassis removed without disconnecting the cord 36 therefrom.

The metal parts of the chassis may be grounded via the conductor 38.

The chassis may be assembled without the transformer and is then encased as just described, the transformer being mounted elsewhere and the secondary thereof connected via suitable leads with the grid terminals.

What is claimed is:

1. An illuminated sign comprising a frame, a transparent panel therein, a luminous grid in the rear of said panel, a reflector behind said grid, a resilient member behind and engaging said reflector, and a member extending across the back and into the side walls of said frame and engaging said resilient member in compression whereby said panel, grid and reflector may be held in said frame by the pressure of said resilient member.

2. An illuminated sign comprising a frame having its outer portions folded at right angles to the face thereof to form rearwardly extending side walls, a transparent panel and a luminous grid and a reflector in said frame and lying below the rear edges of the side walls thereof, resilient members behind said reflector, and means including cross members secured to said side walls and extending across the back of said frame to engage said resilient member in compression whereby said panel, grid and reflector may be held in said frame by the pressure of said resilient members.

3. The sign as claimed in claim 2 wherein the frame is formed from one piece of metal, the center portion being cut out except at the edges and the folded-back portions being slotted to receive the ends of the cross members.

4. The sign as claimed in claim 2 wherein the side walls are provided with integral tongues adapted to be folded over the cross members to secure same in place.

5. The sign as claimed in claim 2 wherein two of the side walls have slots adapted to receive the ends of the cross members.

6. The sign as claimed in claim 2 wherein the frame and cross members have interlocking integral parts whereby they are secured together.

7. An illuminated sign comprising a frame having its outer portions folded at right angles to the face thereof to form rearwardly extending walls, a transparent panel in said frame, a luminous grid engaging the back of said panel, a plurality of reflector strips engaging said grid, cross members secured to said side walls and extending across the back of said frame, and insulating means retained by said cross members and engaging said reflector strips whereby said strips, grid and panel are positioned in said frame.

8. The sign as claimed in claim 7, but wherein said panel, grid, reflector strips, pads and cross members lie below the rear edges of said side walls.

9. An illuminated sign comprising a frame having its outer portions folded at right angles to the face thereof to form rearwardly extending walls, a transparent panel in said frame, a luminous grid engaging the back of said panel, a plurality of reflector strips engaging said grid, cross members secured to said side walls and extending across the back of said frame, insulating means retained by said cross members and engaging said reflector strips whereby said strips, grid and panel are positioned in said frame, and a transformer secured to said frame and having leads connected to said grid.
